Attorney

UNITED STATES PATENT OFFICE.

CARMINE BERARDI, OF PHILADELPHIA, PENNSYLVANIA.

LOCK VALVE.

Application filed June 30, 1921. Serial No. 481,467.

To all whom it may concern:

Be it known that CARMINE BERARDI, a citizen of the United States, residing at Philadelphia, in the county of Philadelphia and State of Pennsylvania, has invented certain new and useful Improvements in Lock Valves, of which the following is a specification.

This invention relates to locking valves, 10 and is adapted mainly for use in connection with the fuel feed line or pipe of internal combustion motors; more specifically applicable to the gas line of motor vehicles, whereby the line may be locked when it is 15 desired to preclude the passage of fuel therethrough to the carburetor of the motor.

A further object of the invention is to provide a locking valve of such construction that it may be readily installed at any 20 desired place in the feed pipe of the motor, and which may be quickly and easily operated by inserting therein a proper key, to either permit the fuel to pass therethrough or to seal the same against such passage.

25 A still further object is to provide a lock valve of simple and inexpensive construction, which is composed of but few simple and readily assembled parts, which has its various parts so-constructed and assembled 30 as to minimize the opportunity for wear, breakage or derangement, which has its plug so applied that the valve can not be taken apart without the introduction thereto of the proper key, and which may be 35 manufactured at low cost.

40 A still further object is to provide a locking valve of the rotary plug type, and wherein the same is wedged upon its seat when in operative position, whereby danger of the same becoming jarred loose from its seat is overcome.

45 With these objects in view, together with others which will appear as the description proceeds, the invention consists in the novel construction, assemblage and arrangement of parts, all as will be described more fully hereinafter, illustrated in the accompanying drawings, and particularly pointed out in the claims.

50 In the drawings:

Fig. 1 is a vertical longitudinal sectional view taken through a valve constructed in accordance with the invention, the plug being in the position it will assume when the 55 pipe line is closed,

Fig. 2 is a top plan view of the improved valve, and

Fig. 3 is a side elevation, parts broken away, showing the plug in unlocked or open position.

The pipe line of the motor vehicle engine is indicated at 4, and is of the usual well known construction, and leads from the source of fuel supply to the carburetor of the engine, as will be understood.

The valve of my invention includes a body or casing indicated at 5, formed of suitable metal and cast in the desired size and appropriate shape. This body or casing, in the present instance, is circular in 70 top plan, and has a bore 6 opening centrally in the top thereof and extending nearly to the bottom of the casing. This bore is circular in cross section for the greater part of its depth, and the side walls 75 thereof taper inwardly near the bottom of the bore to provide a valve seat as at 7. The extreme lower end of this opening or bore is of greatly reduced diameter and is interiorly threaded as shown; this reduced 80 threaded portion being confined within the enlargement 8 at the lower end of the casing.

A fuel passage or duct 9 passes longitudinally through the casing near the lower part 85 thereof and communicates with the seat 7, the said seat intercepting the passage so that the latter communicate with the seat at diametrically opposite points therein. The passage extends upwardly from the seat and 90 communicates with the nipples near the upper end of the casing; these nipples being indicated at 10. The nipples are of such size that the ends of the broken pipe line may be snugly engaged thereover.

95 The locking device for the casing includes the rotatable plug 11, of a size and shape corresponding with the bore of the casing. This plug has tapered walls 12 near its lower end to rest and seat upon the seat 7, 100 and the extreme lower end of the plug is reduced and threaded, forming a shank 13 to engage in the interiorly threaded recess at the bottom of the casing. The construction is such that a tight fit of the plug in 105 the bore is obtained, and danger of leakage of the fluid past the plug is obviated.

The tapered portion of the plug is provided with a passage 14 adapted when the plug is in open position to align with the 110

channel or duct 9 of the casing, to permit of fuel passing from one end of the casing to the other. When, however, the plug is turned so that the channels and duct 9 6 and 14 respectively are out of alinement, passage of any appreciable quantity of fuel beyond the plug will be prevented, as will be obvious. In rotating the plug to closed position, the plug will be slightly withdrawn 10 from the bore, that is, the stem or shank 13 will be lifted slightly from the bottom of the threaded recess, while when the valve plug is turned to such position as to permit the passage of fuel therethrough, the shank 15 or stem will tightly seat in the bottom of the threaded recess and will bind therein. Obviously the tapered portion of the plug will seat firmly upon the tapered portion of the bore when the plug is in open position, and will tend to bind upon its seat. This precludes leakage of fuel in the casing bore, and the binding action of the plug prevents the same turning in its bore, as might be the case were it not so bound, 25 due to vibration of the vehicle when in motion.

The plug is provided with an axial opening or slot 15 to receive a key for operating the locking mechanism of the casing. This 30 locking mechanism may be of any preferred construction, the present illustration showing a number of pins 16 carried in the block 17 set in the casing and tightly fixed therein. These pins are normally projected into 35 the slot of the plug by springs 18, thus holding the plug against rotation. When, however, the proper key is inserted in the slot the pins are forced back out of the slot to free the plug, permitting the plug to 40 be turned to operative position. The upper part of the casing is provided with a spring tongue to engage in suitable notches in the plug, holding the latter in either "on" or "off" positions. The spring is indicated at 45 19 and the notches therefor at 20.

The casing is applied to the fuel line by cutting the pipe 4 and engaging the ends of the latter over the nipples 10, making 50 tight joints to prevent leakage. The owner of the vehicle to which the lock casing is applied will be furnished with a key to operate the particular lock combination with which the casing is provided, and no other key will operate the lock. When it is desired to operate the vehicle the key is inserted in the plug and the latter rotated 55 a quarter turn so as to register the openings 14 and 9. In order to do this slight pressure must be applied to the plug, causing 60 the latter to become firmly seated, as before described, and thus held against becoming loose. The fuel will then pass to

the carburetor as needed. In locking the fuel line, the key is inserted and the plug rotated back a quarter turn, and upon withdrawal of the key the pins 16 will enter the slot 15 and hold the plug against movement.

By constructing the device in the manner described, it is obvious that a safety lock 70 for the fuel line is provided, and one in which tampering by unauthorized persons will be of no avail. It is possible to gain access to the interior of the casing only with the proper key, and by reason of the 75 fact that the entire lower end of the plug is wholly enclosed by a part of the casing wrenches, screw-drivers and the like cannot be employed successfully to operate the valve. The block 17 holding the pins 16 80 may be brazed or in any other manner rigidly affixed in the casing.

I claim:

1. In a locking valve, a casing, a plug fitting therein, a tapered seat in said casing, a tapered portion on said plug fitting upon said seat, the said casing having a threaded recess, a threaded stem on said plug engaged in said recess, and the said plug being in one definite position when the said plug has been turned so that the taper thereof is wedged upon said seat and the threaded stem is limited against further rotary movement in one direction.

2. In a locking valve, a casing having a bore therein, a seat in said casing having tapered walls, the said bore terminating at one end in a threaded recess alined with said bore, the casing having apertures therein communicating with said seat, a plug rotatable in said bore and fitting snugly therein, a tapered portion on said plug resting upon said seat, the said plug having openings therein in said tapered portion adapted to aline with the apertures in said casing, a threaded stem at the lower end of said plug fitting in said recess, and means in connection with said plug for holding the latter against rotation.

3. In a locking valve, a casing having a bore extending inwardly from one side thereof, a seat near the bottom of said bore, the said casing having a threaded recess at the bottom of said bore axially alined with the latter, a plug rotatable in said bore, a tapered portion on said plug resting upon said seat, and a threaded stem at one end of said plug engaged in the said threaded recess.

In testimony whereof he affixes his signature.
